UNITED STATES PATENT OFFICE

2,449,757

TRANSVERSELY SLIDING RAILWAY FROG

Anthony L. Vissat, Pittsburgh, Pa.

Application November 27, 1944, Serial No. 565,253

1. Claim. (Cl. 246—392)

1

This invention relates to a transversely sliding railway frog employed for effecting the crossover from one railroad track to another, and wherein the interruptions in the fixed rails are completed by rail portions carried by a movable frog plate which is shifted in unison with the switch.

Important objects and advantages of the invention are to provide a railway frog of the character described, which is entirely constructed of assembled rolled steel instead of steel castings and in consequence provides a stronger and more durable frog structure, which eliminates all rail gaps and the necessity for guard rails, which maintains the fixed rail ends in perfect level alignment with the frog rails at all times and under all conditions, which is fixedly held in proper position by the travel of the engine and cars thereover, which may be readily kept in cleaned condition, which is simple in its construction and arrangement, compact, conveniently operable, and comparatively economical in its manufacture, installation, and maintenance.

With the foregoing and other objects in view which will appear as the description proceeds, the invention resides in the novel construction, combination and arrangement of parts herein specifically described and illustrated in the accompanying drawing, but it is to be understood that changes in the form, proportions and details of construction may be resorted to that come within the scope of the claim hereunto appended.

In the drawing wherein like numerals of reference designate corresponding parts throughout the several views:

Figure 1 is a top plan view of a railway frog constructed in accordance with the invention with the frog plate being positioned to complete the fixed rails of the main track.

Figure 2 is a side elevational view thereof.

Figures 3, 4 and 5 are sectional views of Figure 1 taken on lines 3—3, 4—4, and 5—5, respectively.

Referring in detail to the drawing 1 denotes the cross-ties upon which the improved frog structure is supported. A flat, elongated, and comparatively narrow base plate 2 is permanently fixed and secured upon the cross-ties by means of spikes or in any other suitable manner. A pair of similar, flat end plates, respectively indicated at 3 and 4, are positioned flatly against the top of the base plate in spaced relation and at respective ends of the latter. The end plates are permanently fixed to the base plate by welding and by a plurality of rivets, respectively indicated at 5 and 6.

The pointed rail end 7, comprising the con-

2

verging rail members 8 and 9, has its pointed terminal permanently secured against the top of the end plate 3 by welding and by means of a plurality of rivets 5. The rail members 8 and 9 are further supported and secured by an interposed filler block 10 and by the fish plates 11 and bolts 12, which latter extend through the fish plates and rail members 8 and 9.

The spaced rail end 13, comprising the converging rail members 14 and 15, has its rail spaced terminal permanently secured against the top of the end plate 4 by welding and by means of the rivets 6. The rail members 14 and 15 are further supported and secured by an interposed and recessed filler block 16, and by the fish plates 17 and bolts 18.

A flat frog plate 19 is positioned flatly on the top of the fixed base plate 2 between the inner ends of respective end plates 3 and 4. The thickness of the frog plate is identical to the thickness of the end plates, so that the top surfaces of the latter and of the frog plate extend on an even plane.

A pair of spaced converging rail members 20 and 21 are permanently fixed to the top of the frog plate 19 by welding and by means of a plurality of rivets 22. The rail members 20 and 21 are further secured by a pair of filler blocks 23 and 24 which are interposed at respective ends of said rail members and secured by fish plates 25 and bolts 26.

The rivets 5, 6 and 22 are arranged in staggered relation on opposed sides of respective rail members, and where necessary the embodied fish plates and filler blocks are notched to provide clearances for the rivet heads, as illustrated in Figure 4.

A pair of stop bars 27 and 28 are positioned against respective bottom side edge margins of the frog plate 19. The stop bar 27 is fixed in position by welding and rivets 29, and the stop bar 28 is detachably secured by bolts 37. The frog plate is considerably wider than the base plate 2 and is laterally shiftable in both directions of the latter to a distance permitted by the stop bars 27 and 28, which abut against the side edges of the base plate. The frog plate is provided with a grease cup 35 and the top of the base plate is formed with channels 36 for lubricating the engagement of the frog plate on said base plate.

The relative positions of the rail members 15, 20 and 8 are such that said members will be in perfect alignment when the stop bar 27 abuts 55 against the side edge of the fixed base plate 2.

The aligned rail members 15, 20 and 8, together with the parallel track rail 31 provide the straight main trackway, as shown in Figure 1.

In like manner, the relative positions of the rail members 14, 21 and 9 are such that the latter will be in perfect alignment when the frog plate 19 is shifted laterally to cause the abutment of the detachable stop bar 28 against the adjacent side edge of the base plate 2. The aligned rail members 14, 21 and 9 in conjunction with the parallel track rail 31 provide the tangent trackway.

The ends of the rail members 20 and 21 are spaced from the respective ends 32 and 33 of the frog plate 19. The terminal of the pointed rail end 7 squarely overlaps and rests upon the top edge margin of the frog plate end 32, and the terminal of the spaced rail end 13 squarely overlaps and rests against the top edge margin of the end 33 of the frog plate 19.

The overlapping engagement of the top end edge margins of the frog plate 19 by the terminals of the rail ends 7 and 13, in the manner stated, constitutes a most important feature of the present invention. While such engagement of said terminals upon the end edge margins of the frog plate will not interfere with the free lateral movement of the latter upon the base plate 2, such engagement will not only aid in maintaining the frog plate flatly in position upon the base plate, but will assure the constant level alignment and registration of the frog rails 20 and 21 with respective rail members of the rail ends 7 and 13 during the travel of engine and cars over the frog structure.

It will be obvious that when a train is traveling on the main trackway and passing over the frog structure, the thrust of such transportation will tend to force and hold the stop bar 27 against the adjacent side edge of the base plate 2, and that when such travel is on the tangent trackway the thrust will tend to force and hold the stop bar 28 against its adjacent side edge of the base plate, whereby perfect rail alignments will be maintained at all times and under all conditions.

The frog plate 19 is freely shiftable in both lateral directions on the base plate 2 by means of any suitable operating mechanism, including connecting links 34 which are joined with either side edge of the said frog plate.

The present invention provides a most efficient, durable and economical frog structure, as it is entirely constructed of rolled steel and assembled, instead of being constructed of steel castings. The embodied rail members are made of sections of conventional track rails, and all involved plates are constructed of rolled steel.

What I claim is:

A railway frog construction of the class described comprising the combination of a fixed flat rolled steel base plate provided with lubri-

cating channels on the top face thereof, a pair of flat rolled steel end plates fixed on respective end portions of said base plate, a flat rolled steel frog plate mounted on said base plate between said pair of end plates and being of a width considerably greater than the width of said base plate, the top surface of said frog plate being disposed on the plane of the top surfaces of said end plates, a lubricating element carried by said frog plate operable for supplying lubrication to said channels, a pair of converging pointed rolled steel rail members having a pointed end portion fixed on one of said pair of end plates, the terminal of said pointed end portion overlapping and seating on the adjacent end portion of said frog plate, a pair of converging spaced rolled steel rail members having the end portions thereof fixed on the other of said pair of end plates, the terminals of said spaced end portions overlapping and seating on the adjacent end portion of said frog plate, a pair of rolled steel rail sections fixedly assembled on said frog plate in spaced relation to each other and having the ends thereof spaced from respective ends of said frog plate, a pair of filler blocks disposed between and secured to respective end portions of said rail sections for reenforcing and maintaining the spaced relation of the latter, said frog plate being laterally adjustable in one direction on said base plate to position one of said pair of rail sections in alignment with the terminal of said pointed rail members and with the terminal of one of said pair of spaced rail members, said frog plate being laterally adjustable in the other direction on said base plate to position the other of said pair of rail sections in alignment with the terminal of said pointed rail members and with the terminal of the other of said pair of spaced rail members, and a stop bar fixed at each bottom side edge portion of said frog plate and extending throughout the length of the latter for engaging respective side edges of said base plate to limit the lateral adjustment movements of said frog plate on said base plate to distances providing the exact alignments of said rail sections with the terminal of said pointed rail members and with respective terminals of said pair of spaced rail members.
